FLUID CONDUIT

Marion W. Barnes, Chicago, Ill., assignor to Universal Oil Products Company, Chicago, Ill., a corporation of Delaware

Application November 26, 1937, Serial No. 176,547

2 Claims. (Cl. 285—56)

This invention particularly refers to improvements in fluid conduits such as tube banks for furnaces, heat exchangers and the like, of the type wherein the tubular elements are expanded at their ends into headers or return bends by rolling.

The utility and primary objects of the invention can be best explained by a brief review of the art which has preceded the invention.

It has long been the practice to provide tube headers or return bends with sharp shouldered grooves in the port into which the tube is rolled and to provide a flare or pronounced taper at the inner end of the port over which the end of the tube is flared or belled. With the advent of tubes for high temperature service, containing alloying elements which materially increase the hardness of the metal or which have a hard coating or surface, the rolling required to sufficiently deform the metal of the tube walls and obtain a good fit between the same and the grooved walls of the tube port resulted in considerable cracking in the rolled walls of the tube, particularly at its flared end. If rolling of this type of tube is stopped before cracks develop, the expanded tube will not fit closely into the grooves and, even with tubes of this type which have been heat-treated at their ends to soften the same, facilitate rolling and prevent pronounced cracking, it has been found that rapid corrosion occurs at the rolled ends of the tubes when they are subjected to corrosive conditions ordinarily present, for example, in cracking service.

This difficulty is only partially overcome by eliminating the pronounced flare or belling at the ends of the tubes and substituting a slight taper throughout the length of the port. Furthermore, this practice presents another difficulty since, with the tapered tube port the metal of the tube walls will creep upon rolling and unless some means is provided for preventing this, the resulting elongation of the tube decreases its expansion to such an extent that the metal of the tube walls will not expand sharply into the grooves of the tube port without excessive rolling.

To avoid both of the above mentioned difficulties, a shoulder or stop was provided in the header or return bend at the end of the tube. By butting the tube end against the shoulder or stop before rolling, elongation of the tube was prevented and a good fit was obtained between the tube walls and the grooved and tapered tube ports without excessive rolling and cracking of the metal. However, this practice involved another serious disadvantage since the inside di-

ameter of the tube port at the shoulder or stop was less than the outside diameter of the tube and, therefore, tubes could not be replaced through this restriction in the port. In replacing a damaged or badly corroded tube, it was necessary to sacrifice a companion tube (i. e., the tube next adjacent the one to be replaced).

In an attempt to overcome the last mentioned difficulty, the height of the shoulder or stop was decreased so that the inside diameter of the port at this point was approximately $\frac{1}{2}$ inch greater than the outside diameter of the tube, the theory being that the tube walls would expand sufficiently upon initial rolling and before substantial elongation of the tube occurred so that the end of the tube would rest against the shoulder or stop. Although it is possible to obtain good results with this method, it is often unsatisfactory in practice because extreme care and skill must be exercised in rolling the tubes into the headers to insure that the tube end will be expanded sufficiently to engage the shoulder or stop before it has become substantially elongated. The rolling operation is, therefore, too critical to insure uniformly satisfactory results.

In the present invention, in order to overcome all of the above mentioned difficulties, instead of providing an integral shoulder or stop in the tube header or return bend, it is provided with a recess adjacent the end of the tube and a metal ring is provided which can be inserted into said recess and against which the end of the tube will bear to prevent the same from creeping. For relatively large diameter tubes this ring may be split so that it may be compressed slightly and sprung into place in the groove. It is preferably made of chrome-alloy steel or other metal resistant to corrosion, and in form may closely resemble a piston ring. With relatively small diameter tubes, a split ring may not be feasible and in such cases the invention contemplates a ring comprising two or more separate arc-shaped pieces which may be individually placed in the groove provided in the tube header or return bend.

The use of a separate ring, as above described, inserted in a groove provided in the tube header or return bend adjacent the end of the tube, permits readily replacement of any individual tube in the nest or bank without sacrificing an adjacent tube. This is accomplished by removing or destroying the ring so that the replacement tube can be inserted through the port in the header or return bend. It is obvious that, with the present invention, the inside diameter of the ring or stop is not limited and may be only sufficiently less

than the outside diameter of the tube to prevent creeping of the latter and thereby obviate excessive rolling of the tube.

It will also be obvious that the features of the invention are applicable to any type of header, return bend or tube sheet wherein the wall thickness at the end of the port into which the tube is rolled is sufficient to permit providing the same with the necessary grooves.

10 The accompanying diagrammatic drawing comprises nine figures. Figures 1, 2, 3, 4, and 5 each illustrate that portion of a tube header, return bend or tube sheet disposed adjacent a port therein into which the end of a tube, also 15 illustrated, is rolled. The five different types of ports above described are illustrated, in the order above mentioned, by the respective Figures 1, 2, 3, 4 and 5. Figure 6 is an end view of one form of split ring provided by the invention and illustrated in section in Figure 5. Figure 7 is a side view of the same ring shown in Figure 6. Figure 8 is an end view of a modified form of ring of the nature provided by the invention and intended for use with tubes of relatively small diameter. Figure 9 is a side view of the same ring shown in Figure 8.

In each of the Figures 1 to 5 inclusive that portion of the header or tube sheet adjacent the port into which the tube is rolled is indicated at 30 1 and a portion of the tube, including the end which is rolled into the header or return bend is indicated at 2.

It will be noted that in Figure 1 the bore of the tube port 3 is substantially straight and 35 slightly larger in diameter than the outside diameter of the tube. Tube port 3 of Figure 1 is provided with a groove 4, the side walls 5 of which have relatively sharp corners and are cut at substantially right-angles to the bottom of the 40 groove and the side walls of the tube port. A flared portion 6, adjacent the inner end of the tube port, over which the end of the tube is flared or bellied is also provided in Figure 1. The tube 45 2 is of relatively hard metallic alloy or has a hard surface and it will be noted with reference to Figure 1, which shows the end of the tube rolled into port 3 and into the serrations provided therein, that the rolling required to bell or flare the end of the tube results in cracks such as indicated at 50 7, and that the expanded tube does not fit closely into the groove 4. It is, therefore, obvious that the manner of joining the tube to the header or tube sheet, as illustrated in Figure 1, is not satisfactory.

55 In each of the Figures 2 to 5 inclusive, the walls of the tube ports are cut on a slight taper to obviate pronounced flaring or bellining of the extreme end of the tube as in Figure 1. In practice a taper of approximately $\frac{3}{8}$ inch to the foot has 60 been found satisfactory, but for better illustration the taper has been somewhat exaggerated in the drawing.

With reference to Figure 2, it will be noted that groove 8 is tapered slightly in a direction 65 opposite to the taper of the tube port, and better contact is obtained between this groove or serration and the expanded walls of the tube. With a relatively soft tube of ordinary carbon steel, for example, the end of the tube, which is located at 70 approximately the dotted line 9 when the rolling operation is started, would be depressed into the serration or groove 10 and shoulder 11 would act as a stop. However, with a relatively hard tube of the nature above mentioned, the rolling will 75 result in an elongation of the tube, as indicated

at 12, due to creeping of the metal. The contact between the expanded tube walls and groove 10 as indicated in Figure 2, is not satisfactory and any further rolling of the tube in an attempt to obtain better contact and prevent leaks must be 5 done with extreme care to avoid cracking or checking of the tube walls due to excessive rolling.

The tube port in Figure 3 is similar to that of Figure 2 except that a shoulder or stop 14, integral with the tube sheet or return bend, which is more pronounced than shoulder 11 of Figure 2, is provided. It will be noted with reference to Figure 3 that there is good contact between the expanded walls of the tube and the grooves 15 8' and 10' and that shoulder 14 acts as an effective stop. However, it will also be noted with reference to Figure 3 that the opening provided between the walls of shoulder 14 is somewhat smaller in diameter than the outside diameter 20 of the tube. This prevents inserting a replacement tube into the tube port through this restricted portion and necessitates removal of a companion tube along with the tube which requires replacement.

25 Figure 4 indicates the result of decreasing the height of shoulder or stop 16, as compared with shoulder 14 of Figure 3, so that the diameter of the tube port at this point is slightly greater than the outside diameter of the tube. The shoulder 30 16 of Figure 4 was often unsatisfactory as a stop for the end of the tube due to the fact that creeping of the metal in the tube walls and elongation of the tube to a point beyond the stop ordinarily resulted from initial rolling and the 35 end of the tube, therefore, did not engage the shoulder or stop 16. Also, due to creeping of the metal in the tube walls, the contact between the expanded walls and the grooves 8'' and 10'' was not satisfactory and further rolling in an attempt 40 to obtain better contact tended to cause cracking or checking of the tube walls.

With the form of tube stop illustrated in Figure 4, difficulty is also encountered in properly 45 installing the tubes. Since the diameter of the tube port at the stop is somewhat larger than the outside diameter of the tube, the tube end cannot be butted against the stop and is apt to either lap or fall too far short of the tube stop. Unless the end of the tube is spaced at just the 50 proper location with reference to the stop, rolling cannot be done in a satisfactory manner and variations in this spacing will result in an irregular tube bank with some headers or return bends projecting beyond the others.

55 Referring now to Figure 5, which illustrates the improvement provided by the invention, the tapered tube port and the grooves 8''' and 10''' are of the same form as those of Figures 3 and 4, but the stops or shoulders 14 and 16 of the respective Figures 3 and 4 are replaced in Figure 5 by a deeper groove 18 into which a metal ring 19 is inserted. Ring 19 is split as indicated at 60 20 to provide for its compression so that it may be slipped into the tube port and allowed to 65 spring into groove 18, this being accomplished, for example, by the use of a tapered sleeve or the like inserted in the extreme end of the port over shoulder 21, into and through which sleeve the ring 19 is forced by a suitable plug or dolly wherever it is compressed sufficiently to enter the tube port and, upon leaving the sleeve, will expand 70 into groove 18. The approximate location of the end of the tube before the rolling operation is started is indicated in Figure 5 by line 22, and 75

since the inside diameter of ring 19, when expanded into groove 18, is appreciably less than the outside diameter of the tube the ring acts as an effective tube stop during the entire rolling operation. This prevents any substantial elongation of the tube due to creeping of the metal upon rolling and the tube walls can, therefore, be expanded into grooves 8''' and 10''' to give a satisfactory fit without excessive rolling.

10 To replace a damaged tube when employing the improvements provided by the invention and illustrated in Figure 5, the end of the tube is cut or chipped from the header or tube sheet in the usual manner and ring 19 is removed. Suitable

15 means may be provided within the scope of the invention to compress ring 19 and remove the same from groove 18 without destroying it, although such means are not illustrated in the drawing. However, since no great expense is involved, ring 19 is ordinarily broken by a sharp blow with a hammer or chisel or by prying up one end of the ring adjacent slot 20 and may then be readily removed from groove 18.

20 Except for the restriction provided by ring 18, the minimum diameter of the tube port of Figure 5 is somewhat greater than the outside diameter of the tube and, upon removal of a damaged tube and removal of ring 19, a replacement tube may be readily inserted through the tube port from the inner face 15 of the tube sheet.

25 End and side views of the ring 19 provided in Figure 5 are illustrated in Figures 6 and 7, respectively which are self-explanatory.

30 Figures 8 and 9 are end and side views, respectively, of a modified type of ring contemplated by the present invention. The type of ring shown in Figures 8 and 9 will ordinarily be found more satisfactory for tubes of relatively small diameter than the type of ring indicated in Figures 5, 6 and 7.

35 The ring 21 of Figures 8 and 9 is divided into three arc shaped portions 28, 28' and 29. It is,

of course, also within the scope of the invention to divide this type of ring into any desired number of pieces. The separate pieces of ring 21 are separately inserted into a groove of the header or tube sheet similar to that of groove 18 in Figure 5 and when all sections of the ring are in place they will prevent each other from falling out of the groove.

40 I claim as my invention:

1. In an apparatus of the class of tube sheets, 10 headers and return bends having a port for the reception of an end of a tubular member, said port being provided with a groove into which a portion of the metal of the tube walls is expanded by rolling to secure the tube in said port, a second groove provided in said port adjacent the end of the tube, and a metal ring insertable into said second groove and adapted to serve as a stop for preventing substantial elongation of the tube 15 upon rolling.

2. In an apparatus of the class of tube sheets, 20 headers and return bends having a port for the reception of an end of a tubular member, said port being provided with a groove into which a portion of the metal of the tube walls is expanded by rolling to secure the tube in said port, a second groove provided in said port adjacent the end of the tube, and a metal ring insertable into said second groove and adapted to serve as a stop for preventing substantial elongation of the tube 25 upon rolling, said port being further characterized in that it is tapered slightly from adjacent the end of the tube to adjacent the opposite end of the port, the minimum diameter of said port being adjacent said opposite end thereof and being slightly greater than the normal outside diameter of the tube before rolling and said ring being further characterized in that its inside diameter, when the ring is in place in said second groove, is appreciably less than the said normal 30 outside diameter of the tube.

35 MARION W. BARNES.
